ABSTRACT

A pistol type nozzle valve having a barrel top, a barrel frame, and a handle grip, usable in especially a gasoline station having a suspended type gasoline feeding means, an inlet being provided at the side of the barrel frame, and an automatic valve closing device being provided in the barrel frame on one side of the inlet opposite the barrel top side, so that the center of gravity is shifted to that side of the nozzle opposite the barrel top, to thereby effect automatic rotation of the barrel top into an upward direction when not in use.

PISTOL TYPE NOZZLE VALVE

BACKGROUND OF THE INVENTION

The present invention relates to a pistol type nozzle valve, and more particularly to a pistol type nozzle valve which nozzle tip is always maintained in an upward position when the nozzle valve is suspended by a hose.

Heretofore, in general pistol type nozzle valves for use in a gasoline station, a handle grip has been used as an inlet so that, in the suspended type gasoline feeding means (U.S. Pat. No. 3,395,723 and British Pat. No. 1,116,781) in which a hose is lowered from a hose reel provided on a ceiling for feeding gasoline into an automobile tank, in order to keep the barrel tip of a pistol type nozzle valve in an upward position, a double-swivel joint of the elbow type is fixed to the root of the handle grip of the nozzle valve so as to rotate it into an upward position parallel to the vertical hose. However, operations such as fastening, dismounting and rotating are drawbacks for gasoline feeding operations, especially for a busy gasoline station.

SUMMARY OF THE INVENTION

The present invention is designed to avoid the drawbacks mentioned above in that, on the side of the central portion of the barrel frame of a pistol type nozzle valve, an inlet is provided and, when a hose is connected to this inlet so as to suspend it by means of the hose, the barrel top of the pistol type nozzle valve is always maintained in an upward position. Also, the center of gravity of the nozzle is arranged to be positioned on a side of the inlet opposite the barrel top to cause the barrel top to automatically rotate into an upward position when released.

OBJECTS OF THE INVENTION

The primary object of the present invention is to provide a pistol type nozzle valve which is easy to handle and is so arranged that its center of gravity is positioned on the opposite side of its barrel top relative to an inlet, so that the barrel top may be positioned upwardly when the nozzle valve is released.

Another object of this invention is to provide a pistol type nozzle valve provided with an automatic closing means on the opposite side of the barrel top relative to an inlet, so as to position the center of gravity of the nozzle valve on the opposite side relative to the barrel top.

A further object of the invention is to provide a pistol type nozzle valve provided with a rotation stop pin on the nozzle for stopping the nozzle valve in a position suitable for feeding gasoline when the nozzle valve is rotated to feed gasoline.

A still further object of the present invention is to provide a trigger restraining means for a pistol type nozzle valve, which is adapted to be operated with one hand when the trigger of the nozzle valve is actuated.

The foregoing objects and the other objects as well as the characteristic features of the present invention will become more apparent and more readily understandable by the following detailed description of the invention when taken in conjunction with the accompanying drawings.

BRIEF DESCRIPTION OF THE DRAWINGS

FIG. 1 is a side view of an actual gasoline station

equipped with a suspended type gasoline feeding means incorporating a pistol type nozzle valve of the prior art.

FIG. 2 is a side view of a gasoline station equipped with a suspended type gasoline feeding means incorporating a pistol type nozzle valve of one embodiment in accordance with the present invention.

FIG. 3 is a cross-sectional view of a pistol type nozzle valve of such embodiment.

FIG. 4 is a part sectional view of the nozzle valve taken along line IV-IV of FIG. 3.

FIG. 5 is a cross-sectional view of the pilot valve for the nozzle valve.

FIG. 6 is a plan view of the push rod of the nozzle valve.

FIG. 7 is a perspective view of a U-shaped frame body into which rolls pins of the nozzle valve are inserted.

FIG. 8 is a side view showing the condition of the pistol type nozzle valve rotated to feed gasoline.

FIG. 9a is a cross-sectional view of a guard for the trigger of the pistol type nozzle valve.

FIG. 9b is a plan view of such guard.

FIG. 10a is a side view of another embodiment of the pistol type nozzle valve having two inlets provided on both sides of the barrel frame.

FIG. 10b is a right side view of the pistol type nozzle valve of FIG. 10a.

DETAILED DESCRIPTION OF THE INVENTION

FIG. 1 illustrates a prior art pistol type nozzle valve of the suspended type used in a gasoline station, wherein the handle grip serves as an inlet. A hose reel device 61 is mounted on a ceiling 60 and houses a reeled-up hose 62 used for feeding gasoline into an automobile gasoline tank. A pistol type nozzle valve 63 is secured at the free end of the hose and, in order to maintain its barrel tip 64 in an upward position when not in use, a double-swivel joint 66 of the elbow type is affixed to the root portion of handle grip 65 so as to allow the nozzle valve to rotate about a horizontal axis into an upward position lying parallel to hose 62. The barrel tip is coupled to the hose in some suitable manner. Such an arrangement is, however, cumbersome during gasoline feeding operations because of the nozzle valve coupling, uncoupling and rotating steps required for each feeding operation.

An improved pistol type nozzle 1 according to the invention is shown in detail in FIG. 3 as comprising a barrel top 2, barrel frame 3, and handle grip 4. Barrel top 2 is an aluminum pipe 5 containing a slender air passage pipe 6, the end 6a of which is opened at the lower side of tip 5a of the aluminum pipe. The opposite end of air passage pipe 6 is connected to the center portion of an air passage supporting member 10.

A coil 7 surrounding pipe 5 is designed for preventing barrel top 2 from slipping out of the gasoline inlet of the automobile tank during gasoline feeding.

The air passage supporting member 10 and a valve means 8 are provided within the elongated barrel frame 3 at the forward end thereof. An inlet 9 (see also FIG. 4) is located at the side of the central portion of the barrel frame, and an automatic valve closing means 11 is provided within the rearward portion of the barrel frame.

A valve seat member 12 of the valve means 8 is fitted within an internal flange 3a of barrel frame by means of an O-ring, and is threaded to member 10. A set

screw 13 threadedly engages the barrel frame and abuts against member 10 to thereby maintain valve seat member 12 in place within flange 3a.

A non-return valve 14 of valve means 8 is slidably connected to air passage supporting member 10 in a manner whereby it is pressed against a valve seat 12b at the inwardly sloping portion at the downstream side of valve seat member 12. Valve 14 is biased into such position by means of a spring 15.

A main valve 16 of valve means 8 is provided at the upstream side of member 12 opposite non-return valve 14, and a pilot valve 17 is connected thereto at its central portion in a manner whereby valve 16 is pressed against valve seat 12a by pilot valve 17.

This main valve 16 and pilot valve 17 are interconnected by a bolt 18 threadedly engaged at the tip of pilot valve 17. A space is provided in valve 16 between head 18a of bolt 18 and a fitting hole 16a of the main valve so that, when the pilot valve is moved to the right, an opening between valves 16 and 17 first occurs depending on the depth of such space, whereafter main valve 16 is opened.

Main valve 16 is provided with small openings 19 to serve as passageways to the downstream side when pilot valve 17 is opened with respect thereto.

As shown in FIG. 5, pilot valve 17 has a main body and a valve rod 17a integral therewith. A slot opening 17b located in rod portion 17a accommodates a trigger 21 extending therethrough.

In FIGS. 3 and 4, trigger 21 is shown in engagement with a notch 17c of pilot valve rod 17a at the back 21a thereof via a push rod 22 and a roll pin 23. Therefore, when trigger 21 is pulled, valve rod 17a is moved to the right, and pilot valve 17 is opened whereafter main valve 16 is also opened.

A pin 40, provided on push rod 22, is fitted in a guide slot 17s formed on the valve rod as shown in FIG. 5, so as to prevent push rod 22 for rotating.

A cap 24 is fitted over the right end of valve rod 17a.

A spring 25 located within the hollow end of rod 17a, bears against push rod 22 and the interior of cap 24. The push rod is thereby maintained in a fixed position, i.e., a position at which the left end of push rod 22 comes into contact with back 21a of trigger 21.

A spring 26, of a stronger spring quality as compared to spring 25, surrounds cap 24 and extends between collar 24a thereof and the interior of a second cap 27. Pilot valve rod 17a is therefore biased into a valve closing position to the left by spring 26.

A U-shaped frame body 28 is shown in FIG. 7 as having slots 28b for the reception of roll pins 23. FIG. 4 shows the frame body in place with its back plate 28a connected by means of a pin 31 to a diaphragm 32 provided in a negative pressure generating chamber 29.

A spring 33 is provided in negative pressure generating chamber 29 and is designed to operate so as to continuously press diaphragm 32 downwardly as shown in FIG. 4, and to cause the two roll pins 23 fitted in slit 28b of frame body 28 to be seated within notch 22a of push rod 22.

Automatic valve closing means 11 is therefore comprised of valve rod 17a, push rod 22, roll pins 23, frame body 28, diaphragm 32, and negative pressure generating chamber 29.

Passages 34 and 35, shown in FIG. 4, are provided for connecting negative pressure generating chamber 29 with an air chamber 36 located in a void between valve

seat member 12 and the main body, and an air chamber 10a (see FIG. 3) of air passage supporting member 10.

An elbow 41 is rotatably secured to inlet port 9 by means of a fitting nut 42. This port opens into the side of barrel frame 3 at approximately the central portion thereof. A strainer 43 and a coupling 44 are secured to elbow 41 at the inlet end thereof by means of a fitting nut 45. A hose 20 (see also FIG. 2) is connected to coupling 44.

Curved portion 21b (FIG. 3) of trigger 21 extends outwardly of barrel frame 3, and a guard 37 (FIGS. 9a and 9b) for the trigger is provided to cover curved portion 21b. One end of guard 37 is removably secured to barrel frame 3 by a pin 38, and the other end thereof is removably secured to handle grip 4 by a pin 39.

A metal restraining member 46 is pivotally secured by a pin 47 to guard 37 within a central elongated slot 37a thereof. Another pin 51 on guard 37 extends into a slot 49 provided in member 46. A spring 48 surrounding pin 47 has one end thereof fixed to the guard and the other end thereof seated on restraining metal member 46 to thereby bias restraining metal member 46 into a clockwise turning position about pin 47. Such a position is limited by means of pin 51 in engagement with an end of slot 49. Notches 46a and 46b, for setting the opening of the valve at two levels, are provided at the inner edge of member 46 and are engageable with a tip 21c of curved portion 21b of the trigger.

An outwardly extending rotating stop pin 52, as seen in FIG. 4, is provided on barrel frame 3 at the periphery of inlet port 9 so as to restrict the rotation of elbow coupling 41 as it bears against the outer wall of the coupling. Such location of the stop pin with its restricting function permits the gasoline feeding operation to be conveniently carried out as handle grip 4 is grasped and pistol type nozzle valve 1 is inserted into the gasoline inlet of an automobile tank. FIG. 8 shows the position of the pistol type nozzle valve just prior to the time rotation stop pin 52 bears against the outer wall of elbow coupling 41 to prevent further rotation. When further rotated about seventy degrees counterclockwise, elbow coupling 41 comes into contact with rotation stop pin 52 to completely stop.

In the embodiment shown in FIGS. 10a and 10b, inlet ports 9 and 9' are provided on both sides of barrel frame 3, and elbow 41 is formed as Y-shaped to prevent the nozzle valve from turning to one side.

The operation and function of the present invention will now be described. Referring to FIG. 2, pistol type nozzle 1 is manually lowered from ceiling 60 as its hose 20 is unreeled from housing 61. Barrel top 2 extends upwardly during lowering, after which nozzle 1 is rotated to the position shown in FIG. 8 for insertion of its nozzle tip into the gasoline inlet of an automobile tank. Rotation stop pin 52 bears against the side of elbow 41 to stop the nozzle in its FIG. 8 position, thereby rendering it easy to operate since hose 20 in no way interferes with the grasping of handle grip 4.

By initially pulling on trigger 21 with the index finger, and hooking the middle finger and the ring finger against the outside of guard 37, back portion 21a of trigger 21 moves push rod 22 to the right as in FIG. 3 thereby also moving the two roll pins 23 to the right. Since pins 23 are seated within notch 17c, valve rod 17a is also moved to the right. Therefore, pilot valve 17 is first opened, whereby the gasoline flows to the downstream side of main valve 16 through small openings 19

of main valve 16, so that the back pressure on main valve 16 is decreased. By further pulling on trigger 21, main valve 16 is opened along with vale rod 17a of pilot valve 17 and the gasoline flows to the downstream side, thereby opening non-return valve 14 as it is pushed against its spring 15.

The initially contracted flow of gasoline at the tapered portion of valve means 8 creates a negative pressure due to a venturi effect and air is drawn in from end 6a of pipe 6 through passage 12c opening here. Therefore, when end 6a is blocked as the gasoline level in the automobile tank rises, the air is checked from flowing from air passage 6, so that the pressure in negative pressure generating chamber 29 interconnecting passage 12c with passages 34 and 35 becomes negative. Diaphragm 32 is pushed up out of chamber 30 with the atmospheric pressure on the down side thereof, and roll pins 23 connected with diaphragm 32 by frame body 28 are also pulled upwardly out of notch 22a of push rod 22, although the pins do not move out of contact with end 17d of notch 17c.

With such operation, push rod 22 disengages from valve rod 17a so as to compress spring 25 and thereafter returns to its original position together with the roll pins by means of spring 26, to thereby close main valve 16 and pilot valve 17.

Then, as trigger 21 is released, push rod 22 is returned to its original position of FIG. 3 by means of spring 25. Notch 22a of the push rod is therefore again located beneath pins 23 for the reception thereof so that valve rod 17a and push rod 22 are again interconnected by means of roll pins 23 as shown in FIG. 4.

Depending on the quantity of gasoline to be fed, the trigger is pulled until its tip 21c lies above notch 46a, for example. Member 46 is then lifted with the middle finger so as to engage notch 46a with tip 21c of the trigger; the valve opening at this notch is therefore maintained. That is to say, since trigger 21 is continuously pressed by spring 26, notch 46a and tip 21c are still in engagement with one another through the friction therebetween, and cannot be disengaged.

In order to disengage them, trigger 21 is further pulled slightly to permit member 46 to be returned to its original position by means of spring 48. Tip 21c of the trigger is then disengaged and returns to its position of FIG. 3.

After gasoline feeding operation is completed and barrel top 2 is removed from the gasoline inlet of the automobile tank, the barrel top automatically rotates toward an upward position about coupling 41 since the center of gravity of nozzle 1 is located on the grip 4 side of the coupling. When released, the nozzle is retracted into housing 61 along with hose 20.

Although the pistol type nozzle is described herein with reference to a gasoline feeding means of the suspended type, the present invention is not restricted thereto. By supporting the elbow coupling of the present nozzle on the nozzle cradle of a conventional ground type gasoline feeder, the barrel top will likewise automatically rotate toward an upward position.

From the foregoing, it can be seen that an efficient and highly effective pistol grip type nozzle has been devised. The inlet is provided on the side of the barrel frame thereof, and the trigger, the automatic valve closing device, and the handle grip are located on one side of such inlet thereby shifting the center of gravity to that side opposite the barrel top. Therefore, the bar-

rel top automatically rotates toward and into an upward position to facilitate an easier gasoline feeding operation.

Since the rotation stop pin is provided near the outer wall of the inlet coupling for controlling the rotary position of the nozzle valve, any interference of the operator's hand with the hose as he holds the handle grip, substantially avoided.

Also, since the restraining metal member for the trigger is biased outwardly into a disengaged position, disengagement becomes easy when desired. The restraining metal member is located just beneath the trigger so that, by merely placing the index finger on the trigger and lifting the restraining metal member with the middle finger, it is possible to restrain the trigger and to operate the nozzle with one hand.

Moreover, since the automatic valve closing device is provided on one side of the inlet coupling, there is no need to provide a special weight, spring, or the like, to assist in nozzle rotation.

What is claimed is:

1. A pistol type nozzle valve for gasoline feeding comprising an elongated barrel frame having a valve means and a trigger element for opening and closing said valve means, a barrel top connected to said frame at one end thereof, a handle grip connected to said frame at the opposite end thereof, inlet means opening into a side of said frame between said top and said grip, said inlet means including a pivotable elbow coupling and a gasoline inlet hose capable of being suspended from an overhead support being connected to said coupling, whereby the nozzle valve may be suspended from said hose.

2. The nozzle valve according to claim 1, wherein said grip and said top are so positioned relative to said inlet means as to locate the center of gravity of the nozzle valve on a side of said inlet means opposite said barrel top so as to cause said barrel top to automatically rotate toward and into an upward position to facilitate easier gasoline feeding.

3. The nozzle valve according to claim 2, wherein said inlet means further includes a rotation stop pin extending outwardly of said barrel frame adjacent said coupling to thereby limit rotation of the nozzle valve about said coupling as said pin bears against a portion thereof.

4. The nozzle valve according to claim 2, wherein a automatic valve closing means is located in said barrel frame at said one side of said inlet opposite said barrel top so as to further insure location of the center of gravity at said side.

5. The nozzle valve according to claim 4, wherein said automatic valve closing means comprises said trigger element mounted within said barrel frame for opening and closing said valve means so as to open and close said inlet means, said closing means further comprising a valve rod having a transverse opening through which said trigger element extends, a push rod located within an axial opening of said valve rod and in contact with said trigger element to be axially moved thereby, a roll pin seated within a transverse notch provided in said push rod, a U-shaped frame member having slot therein for the reception of said roll pin, a diaphragm connected to said frame member, and a negative pressure generating chamber located on one side of said diaphragm to effect movement of said roll bar into and out of said notch.

6. The nozzle valve according to claim 1, further comprising a trigger guard connected to said barrel frame and said handle grip and extending over said trigger element, a restraining metal member pivotally connected at one end thereof to said guard within an axial opening of said guard, a spring on said guard being in engagement with said restraining metal member to spring bias said member outwardly of said trigger element, and notches located at the inner surface of said member for engagement with said trigger element to

10

limit flow through said inlet means upon actuation of said trigger element.

7. The nozzle valve according to claim 1, wherein said valve means comprises a main valve and a cooperating pilot valve, said pilot valve being openable by means of said trigger element, and means being provided to permit back pressure on said main valve to be lowered to facilitate opening of said main valve upon opening said pilot valve.
